Francis C. Heabner,
ATTORNEY.

UNITED STATES PATENT OFFICE.

CLARENCE I. WRIGHT, OF FAIRMEAD, CALIFORNIA.

CARRIAGE FOR DRAG SCRAPERS.

1,409,509.

Specification of Letters Patent. Patented Mar. 14, 1922.

Application filed March 21, 1921. Serial No. 454,124.

To all whom it may concern:

Be it known that I, CLARENCE I. WRIGHT, a citizen of the United States, and resident of Fairmead, in the county of Madera and the State of California, have invented a new and useful Improvement in Carriages for Drag Scrapers, of which the following is a specification.

My invention relates to a wheel attachment for a drag dirt scraper and means for guiding the scraper bowl for filling and dumping, its object being to permit the person manipulating the scraper to easily direct the movements of the scraper bowl by turning a wheel adjacent to the seat in which the operator can ride. I accomplish this and other objects hereinafter set forth by means of the device illustrated in the accompanying drawings in which Figure 1 is a top view of the completed scraper and frame. Figure 2 shows the chain and pulleys arranged for operating the scraper from the front end. Figure 3 is a side view of the device shown in Figure 1. Figure 4 is a sectional view 25 of the device along the line $x-x$ in Figure 3. Figure 5 is a separate view of the handle. Figure 6 is a front view of a pulley.

In said drawings C and C^1 are main parallel longitudinal beams which are connected at the front end by a cross beam D. At the rear ends of beams C and C^1 are inside projections E and E^1 which carry an axle F on which ground wheels B and B^1 can rotate. G is a chain attached at one end to each of the ends of cross beam D at its approximate center having a hook G^1 to attach to a tractor pull. H and H^1 are platform supports attached to beams C and C^1 and extend backward therefrom. These supports carry a platform J at the rear of the wheels B and B^1 . Platform J carries an upright seat post K and a seat K^1 attached to the top thereof, and also two posts L and L^1 which support at the top a shaft M carrying a chain wheel M^1 , and a crank M^2 by which crank the shaft M can be turned. On the top of the main beams C and C^1 , and adjacent to the front end thereof are upright posts N and N^1 which are connected at the top by a tie N^2 . At the rear of said beams, to wit, approximately at the location of the ground wheels are upright posts O and O^1 . A tie P connects posts N and O, and a tie P^1 connects posts N^1 and O^1 at the top. In my drawings I have shown the posts O and O^1 integral with ties P and P^1 , although they

may be formed separately and attached together. Q and Q^1 are supports for the scraper bowl. They are attached at the bottom to beams C and C^1 . They extend upward and the upper portion is bent at an angle and connected with ties P and P^1 . These supports are located between posts O and N , and O^1 and N^1 . R are additional braces to support the platform J. S is an ordinary sliding scraper. The form shown is what is commonly known as the Fresno scraper. It consists of a bowl S^1 , two front shoes S^2 and a rear handle S^3 . At the side ends of the scraper bowl S^4 and S^5 I have attached eyes S^{4a} and S^{5a} near the center of gravity of the bowl by which eyes the bowl is suspended from braces Q and Q^1 by means of chains S^6 and S^7 . S^8 is a hitch consisting of two rods, one end of each rod being pivoted to opposite sides of the bowl near the front, and the other ends being pivoted to the cross beam D. At the approximate center of tie N^2 I have attached a pulley T^2 . T is an endless chain carried on, and extending between pulleys T^2 and chain wheel M^1 . The handle S^3 of the scraper is attached at one end to the scraper bowl and at the upper end is pivoted to the chain T. It will be noted that by turning the crank M^2 the lever S^3 will be moved toward the front or toward the back, thus placing the scraper bowl in position for filling, for carrying, or for dumping. The scraper bowl can be given these different positions by the operator while he remains on his seat at the rear of the platform by turning the wheel M^1 . U is a shoe on the under side of the front end of the frame of the scraper to limit its downward movement and to make it drag more easily when the front end of the frame is lowered. It will be noted from the drawings that the posts N and N^1 lean slightly forward, and toward the center of the frame, and the forward ends of ties P and P^1 are closer together than the rear ends of those ties, this construction tending to give greater strength to the truss construction.

When the scraper is operated by a tractor, the driver of the tractor can rotate wheel M^4 , which in turn rotates chain wheel M^5 attached thereto, which moves chain T. This combination is inoperable unless the chain T is extended to chain wheel M^6 as shown in Figure 2. Y and Y^1 are adjustable supports for wheels M^4 and M^6 . The double pulley T^3 is an intermediate support for chain T.

Having described my invention I claim as new and ask for Letters Patent:

1. In a device of the character described the combination of a base frame supported on wheels, having upright supports at the front and rear of the base frame connected with ties, a scraper bowl suspended from the upper portion of the supports, said scraper bowl having a handle extending upwardly attached to the back of the bowl, an endless chain carried on pulleys at the front, and at the rear of the frame, the upper end of said handle being attached to the chain, and independent means for rotating said pulleys at will, substantially as described.
2. A frame consisting of under beams, upper beams, and connecting posts, traction wheels adapted to carry the frame, a scraper bowl suspended within the frame by means of pliable supports attached to the upper portion of the frame, means for tipping the

scraper bowl consisting of a handle attached to the scraper bowl and extending upward, and means for moving the handle and the bowl consisting of an endless chain carried on pulleys, the upper end of the handle being attached to the chain so that it will move with the chain, and means for moving the chain at will by a crank, adapted to turn one of the pulleys carrying the chain.

3. In combination a frame carried on wheels, the frame having vertical supports a scraper bowl suspended within the frame, and from the frame, and in front of the wheels, and means for tipping the bowl consisting of a handle attached to the back of the bowl and extending in an upward direction said handle adapted to be moved by an endless chain carried on pulleys attached to the frame, and hand means for actuating the chain.

CLARENCE I. WRIGHT.
